UNITED STATES PATENT OFFICE.

JOHN H. KEYSER, OF NEW YORK, N. Y.

RECESS SUMMER-PIECE FOR STOVES.

SPECIFICATION forming part of Letters Patent No. 400,689, dated April 2, 1889.

Application filed October 8, 1888. Serial No. 287,469. (No model.)

To all whom it may concern:

Be it known that I, JOHN H. KEYSER, a citizen of the United States, residing at New York, in the county of New York and State 5 of New York, have invented certain new and useful Improvements in Recess Summer-Pieces for Stoves; and I do hereby declare the following to be a full, clear, and exact description of the invention, such as will enable 10 others skilled in the art to which it appertains to make and use the same.

The object of my invention is to provide a novel style of fire-place recess summer piece, hood, or cell adapted for the reception of a 15 stove as a substitute for a coal-grate, all of which, except its finishing frame-piece, may have been removed from the fire-place, said summer-piece being furnished with a stove-pipe collar, to which the stove may be connected, and with a reducible flange or rim of 20 sheet-iron, by which it can be fitted to different shapes and sizes of fire-places.

The invention enables the householder to economize the room which the stove would 25 require if the stove were set entirely outside the fire-place, and at the same time aids the efficiency of the stove for reflecting heat, while the cost of fitting the same to a fire-place is very slight, and thus householders at 30 a small cost can readily have a stove set in a fire-place as a substitute for a removed grate, and when necessary have the stove and its summer-piece removed and the grate and its attachments readjusted to the fire-place and 35 the finishing frame-piece of said grate, which is already in place.

In the drawings, Figure 1 is a perspective view of my improved recess summer-piece for stoves. Fig. 2 is a front view showing the 40 frame-piece of a fire-place with a stove inserted within the same and into the fire-place, the stove being shown slightly in perspective. Fig. 3 is a longitudinal vertical section of a fire-place with my invention and a stove applied therein, and Fig. 4 is a horizontal section of a fire-place and the summer-piece on a line below the cap portion of the summer-piece.

A indicates my improved recess summer 45 piece, hood, or cell for stoves, the same con-

sisting of an arching and concave cast-metal cap portion, B, surmounting a curved vertical sheet-iron body portion, a, which is somewhat in form of a half-cylinder from its upper edge, a', to its lower edge, a''. The cap 55 portion B extends down to the hearth of the fire-place in the form of an open or skeleton frame, a³ a⁴, said frame being cast with it and formed with a right-angular bolting or riveting flange, e, at its outer edges, which flange 60 is continued around the cap portion and also as a stiffener simply around the lower tie-piece, a³, of the frame.

To the skeleton frame a³ a⁴ the curved body portion a is bolted or riveted in the manner 65 presently described. The said body portion a is formed with right-angular flanges or rims e', of considerably greater width than the space which at any time may exist between the fire-place jambs and the edges of the 70 summer-piece A', and similar sheet-iron flanges or rims, lettered e', to those e' on the body portion a are bolted or riveted upon the flanged edge of the cap portion B. These latter flanges are also of considerably greater 75 width than any space which may exist between the arch or bridge of the fire-place and the summer-piece. Through the above-mentioned flanges or rims and the flanges of the skeleton frame a³ a⁴, as well as the lower and 80 upper edges of the curved body portion a and the lower edge of the cap portion B, bolts or rivets a⁶ a⁷ a⁸ are passed, and thus the cap and body portion are firmly united together.

The important purpose of the flanges or 85 rims of the curved body and the cap portions will be presently described. The cap portion B is cast in concave form to exactly correspond with the upper edge, a', of the body portion a, while above said edge it is made in 90 arch or hood form, as shown, so as to form a complete cap or cover for the chamber of the body portion a, as shown in Figs. 1 and 3, and by this construction it is also rendered capable of serving as a reflector to throw the heat 95 of the stove C out into the room when the stove and summer-piece are in place, as indicated in Fig. 3. The cap B is cast with a front horizontal collar, d', into or over which the stove-pipe collar d is made to fit snugly 100

when the stove is in place, as shown. To the rear side of the cap and coinciding with the collar d' another collar, d^2 , of angular or curved form, is bolted, this serving to direct the products of combustion upward into the draft-flue D of the chimney D', as shown, and when desirable as a means of attachment for a hot-air pipe. The horizontal extension of the body and cap portions of the summer-piece into the fire-place are preferably not made as great as the horizontal area of the recess of the fire-place, in order to have a vertical space or chamber, F, between the back of the summer-piece and the back wall of the fire-place, as illustrated. By such construction and arrangement room is afforded for employing the back upturned collar, d^2 , and the section of stove-pipe for increasing or directing the draft up the chimney.

Referring to the description of the sheet-iron flanges or rims e' , I will now set forth their great utility. These flanges or rims, by being made of much greater width than the space between the walls of the fire-place and the cap and body portions of the summer-piece, and constructed of thin metal—as, for instance, sheet-iron, or of other suitable material similar in thickness to sheet-iron—can with the tinner's shears be reduced in width and brought to a shape suited to a recess of either a circular, oval, or square fire-place, and thus when a summer-piece of given size and shape is carried to a dwelling with all its parts bolted together the workman will not be obliged, as is often the case, to return to the shop for another summer-piece because the one at hand does not fit or suit, being either too small or too large, or adapted for a square instead of an oval or rounded fire-place. On the contrary, he will simply be obliged to clip off with the shears the outer edges of the sheet-iron flanges or rims e' until they are brought to the proper size and form to fit a given style of grate or finishing frame, A', which has been left in its place on the removal of the grate. In this manner I am enabled to make provision for supplying the trade with summer-pieces having reducible sheet-metal flanges or rims, and which can in a very short time and at little expense be adapted for fire-places already furnished with grate-frames or finishing-pieces A', thus adapting fire-places previously used with grates for the reception of a stove, as C, and saving the expense of new finishing-frame pieces.

I do not claim herein the stove shown, as I intend applying for a separate patent therefor.

What I claim, and desire to secure by Letters Patent, is—

1. The summer piece, hood, or cell A for a stove, comprising the cast-iron cap portion B, of arched and concave form, skeleton frame $a^3 a^4$, bolting-flange e , inner stove-pipe collar, d' , and curved sheet-iron body portion a , bolted to the skeleton frame of the cap portion, substantially as described.
2. The summer-piece A for a stove, comprising cap portion B, skeleton frame $a^3 a^4$, curved body portion a , flange e , inner collar, d' , and sheet-metal reducible flange or rim e' , bolted to the flange e , substantially as and for the purpose described.
3. The summer-piece A, comprising the cast-iron cap portion B, of arched and concave form, skeleton frame $a^3 a^4$, the curved body portion a , the inner stove-pipe collar, d' , cast on the cap portion, the outer upturned collar, d^2 , connected to the cast-iron cap portion, the bolting-flange e , and the sheet-metal reducible flange e' , substantially as and for the purpose described.
4. The summer-piece A for a stove, comprising the skeleton frame $a^3 a^4$, cast-iron cap portion B, and body portion a , both made of less horizontal extension than the recess of the fire-place and provided with collars $d' d^2$, flange e , and reducible sheet-metal flange or rim e' , substantially as and for the purpose described.
5. The summer-piece A for a stove, comprising the cast-iron cap portion B and body portion a , and skeleton frame $a^3 a^4$, said portions B and a being both made of less horizontal extension than the recess of the fire-place and provided with collars $d' d^2$ and flange e , substantially as and for the purpose described.
6. A summer-piece for a stove, having its curved sheet-metal body portion a provided with reducible flanges which are of metal homogeneous therewith and made in one piece, and applied in combination with an arched cap portion forming an extension of the body portion, substantially as described.
7. A summer-piece for a stove, having its arched cap portion B, its inner collar, and its skeleton frame of homogeneous metal and made in one piece, substantially as described.

In testimony whereof I hereunto affix my signature in presence of two witnesses.

JOHN H. KEYSER.
